UNITED STATES PATENT OFFICE.

MERLE J. WEST, OF MILWAUKEE, WISCONSIN, ASSIGNOR TO SIMPLEX ALARM COMPANY, OF MILWAUKEE, WISCONSIN, A CORPORATION OF WISCONSIN.

DESIGN FOR A GONG-CASING.

58,846.

Specification for Design.

Patented Aug. 30, 1921.

Application filed March 10, 1921. Serial No. 451,306. Term of patent 7 years.

To all whom it may concern:

Be it known that I, MERLE J. WEST, a citizen of the United States, and resident of Milwaukee, in the county of Milwaukee and State of Wisconsin, have invented a new and original and ornamental Design for a Gong-Casing, of which the following is a specification, reference being had to the accompanying drawing, forming part hereof.

In the drawing:

Fig. 2 is a side view thereof.

I claim—

The ornamental design for a gong casing as shown.

MERLE J. WEST.
